UNITED STATES PATENT OFFICE.

OLIVER A. MILLER, OF BROCKTON, MASSACHUSETTS.

DESIGN FOR AN IRONING-TOOL.

SPECIFICATION forming part of Design No. 26,040, dated September 15, 1896.

Application filed July 31, 1896. Serial No. 601,248. Term of patent 14 years.

To all whom it may concern:

Be it known that I, OLIVER A. MILLER, of Brockton, in the county of Plymouth and State of Massachusetts, have invented and produced a certain new and original Design 5 for Ironing-Tools, of which the following is a specification, reference being had to the accompanying drawings, forming a part thereof:

Figure 1 is a side view of an ironing-tool 10 embodying my design. Fig. 2 is an end view of the same. Fig. 3 is a perspective view.

The leading features of my design are the convex face and concave faces formed on opposite sides of the tool.

15 *a* represents an ironing-tool having the broad convex face 2, which presents a salient curve when viewed from the side, as in Fig. 1, and from the end, as in Fig. 2. The tool

has parallel faces 3 3 and tapering faces 4 4, the latter being connected by the curved face 5, which presents a reentrant curve of long radius when viewed from the side, this curve being substantially parallel with that of the face 2, and a salient curve of short radius when viewed from the end. 25

I claim—

The design for an ironing-tool, substantially as shown and described.

In testimony whereof I have signed my name to this specification, in the presence of 30 two subscribing witnesses, this 29th day of July, A. D. 1896.

OLIVER A. MILLER.

Witnesses:

C. F. BROWN,

A. D. HARRISON.
